[57] CLAIM

The ornamental design for a utensil hook for apertured boards, substantially as shown.

DESCRIPTION

FIG. 1 is a perspective view of the utensil hook for apertured boards showing our new design;

FIG. 2 is a top plan view;

FIG. 3 is a rear elevational view;

FIG. 4 is a side elevational view taken from the left of FIG. 1;

FIG. 5 is a front elevational view;

FIG. 6 is a bottom plan view.
